United States Patent Office.

FRANCIS CLAUSEN, OF SAN FRANCISCO, CALIFORNIA.

Letters Patent No. 82,291, dated September 22, 1868.

IMPROVED BELT-BUCKLE.

The Schedule referred to in these Letters Patent and making part of the same.

TO ALL WHOM IT MAY CONCERN:

Be it known that I, FRANCIS CLAUSEN, of the city and county of San Francisco, State of California, have invented an Improved Belt-Buckle; and I do hereby declare the following description and accompanying drawings are sufficient to enable any person skilled in the art or science to which it most nearly appertains to make and use my said invention or improvements without further invention or experiment.

The object of my invention is to provide an improved buckle for ladies' belts, so constructed that the belt can be quickly and easily tightened or loosened, and when once confined will not draw out or become loose, and one in which the necessity of piercing holes in the belt and thus destroying it is avoided; and consists of a buckle of the desired form, having a bevelled longitudinal catch or lip on its under side, projecting backward at an angle. A piece of metal having an opening in it similar to the buckles now in use, has one end of the belt passed through and secured to it. This piece of metal turns on a shaft, and has its bearings at each end of the buckle. An arm or lever projects from the centre of this piece of metal, and is bent upwards through a hole in the buckle, which, when the buckle is closed, fits closely down against the buckle, allowing the bevelled longitudinal catch to enter the slot in the piece of metal and hold the belt.

To more fully explain my invention, reference is had to the drawings accompanying this specification, and forming a part of the same, in which—

Figure 1 is a front view.

Figure 2 is a back view.

Figure 3 is an end sectional view.

A represents a belt-buckle, having on the under side the bevelled lip or catch B, which projects at an angle, and has its upper portion filed off, so as to present a sharp edge to the belt. A bar, C, turns on a shaft, and has its bearings at each end of the buckle. This piece of metal is provided with a longitudinal slot, a, through which one end of the belt passes, when it is doubled back and fastened. Projecting from the centre of this piece of metal or bar C, is an arm or lever, b, which is bent upwards through the hole D. This arm has a head at its end, and a slot underneath, which fits closely down upon the buckle when it is closed.

To use my buckle, the belt, after having one end fastened to the slotted bar C, is passed around the waist, and the opposite end passed through the same opening through which the other end was passed, and drawn as desired; when, by pressing the lever b with the finger, until it shuts down close upon the buckle, the longitudinal lip is forced through the opening in the slotted bar C, and presses against the belt, thus holding it securely without piercing the belt with holes.

Having thus described my invention, what I claim, and desire to secure by Letters Patent, is—

In a belt-buckle, the bevelled projecting lip B, in combination with the slotted bar C, rotating on its axis, as shown, and operating the lever b, the whole constructed and arranged substantially as and for the purpose described.

In witness whereof, I have hereunto set my hand and seal.

FRANCIS CLAUSEN. [L. S.]
